[57] CLAIM

The ornamental design for an inflated baby cushion for breast feeding, as shown and described.

DESCRIPTION

FIG. 1 is a top view of the inflated baby cushion for breast feeding incorporating my new design.

FIG. 2 is a front view.

FIG. 3 is a right side view with the left side view being a mirror image thereof.

FIG. 4 is a bottom view.

FIG. 5 is a rear view.

FIG. 6 is a perspective view; and,

FIG. 7 is a perspective view showing the cushion in use, "The broken lines are for environmental purposes only and form no part of the claimed design."
